Incorporated, Miami, Fla., a corporation of Indiana

Application August 23, 1957, Serial No. 47,482

Term of patent 14 years

(Cl. D13—1)

FIG. 1.

FIG. 2.

*FIG. 3.**FIG. 4.*Figure 1 is a front elevational view of a building showing my new design.

Figure 2 is a fragmentary top view thereof with portions shown broken away for purposes of illustration only.

Figure 3 is a side elevational view, and

Figure 4 is a rear elevational view.

The dominant feature of my design resides in the portions shown in full lines. Further, the side of the building not shown on the drawings is substantially similar to the side elevation shown in Figure 3.

I claim:

The ornamental design for a building, substantially as shown and described.
